UNITED STATES PATENT OFFICE

JUAN CORNET Y OLIVERAS, OF BARCELONA, SPAIN

PUMP

Application filed March 7, 1929, Serial No. 344,967, and in Spain February 25, 1928.

The pump according to the invention, is simple in construction and operation, and it is valveless, reversible and always available for immediate use. In its operation there 5 is no intermittent flow of liquid, and a minimum expenditure of power is required.

According to the invention, on the whole length of the inner periphery of a cylindrical casing, is arranged a flexible tube of rubber, or other suitable substance of considerable elasticity, the ends of the said tube communicating with the suction and delivery branches of the pump respectively. A driving shaft extends axially into the cylinder 15 and carries, within the cylinder, a supporting member which projects in opposite direction from the shaft toward the inner circumferential wall of the cylinder. Levers are pivoted to the opposite ends of this member and these 20 levers carry at their free ends rollers which are adapted to bear against the resilient tube. The free end of each lever is connected by a brace rod to the opposite end of the supporting member, and these rods are provided 25 with means for varying their effective lengths to adjust the pressure of the rollers against the tube. As the shaft revolves, the tube is compressed by the rollers and the fluid is thereby forced out of one end of the 30 tube and drawn in at the other end continuously.

A pump, constructed according to the invention is illustrated in the accompanying drawings, in which:—

Figure I shows a side view of the pump, 35 partially in section,

Figure II is a side view showing the exterior form of the pump,

Figure III is a section on the line A—B of 40 Figure II,

Figure IV is a plan view of the mechanism,

Figure V is a detail of the turnbuckles.

The invention comprises the construction hereinafter described with reference to the 45 accompanying drawings. Within a cylindrical casing 1, is a central shaft 2, projecting through the fixed side wall 3. The said shaft 2, which is mounted in ball bearings, has on its projecting end a driving pulley 4, 50 and the other end, which is in the interior of

the cylindrical casing 1, carries a supporting member 5 which projects radially in opposite directions from the shaft. At the outer ends of the member 5 are arranged studs 6 and 6' on which are pivoted levers 7 and 7', respectively. On the free ends of the levers are mounted compression rollers 8 and 8', adapted to bear against the tube. A brace rod b connects the stud 6' on one end of the supporting member with the stud 9 on the free end of the lever 7' at the opposite end of said member, and similarly, a brace rod b' connects the stud 6 on the supporting member with the stud 9 on the lever 7. The rod b is provided with a turnbuckle 10, and the 55 rod b' is provided with a turnbuckle 10'. By means of these turnbuckles, the lengths of the rods can be varied to adjust the pressure of the rollers against the tube. On the whole length of the inner periphery of the 60 casing 1 is arranged and bearing thereupon a strong flexible tube 11 of rubber or other suitable substance. This tube tends quickly to assume its initial cylindrical form after it has been compressed or flattened owing to the 65 powerful elasticity of the thick wall. The ends of this tube project to the outside through openings 12 and 13 in the casing 1, and may cross before doing so. They are in addition connected to the suction and delivery pipes so that no escape of fluid can occur. The simplicity of the construction can 70 be seen from the drawings.

The surrounding air is excluded from the apparatus by means of the wall or cover 14 75 screwed to the casing 1.

The operation of the pump, in accordance with the invention is as follows:—The turnbuckles 10 and 10' are so arranged that the rollers 8 and 8' compress the tube 11 until it 80 is completely closed and the flow of fluid through its interior arrested. The pulley is now driven, and causes rotation of the compression rollers 8 and 8' about the shaft 2. These rollers compress the tube against the 85 cylindrical wall of the casing 1 as they move. The tube 11, owing to its considerable elasticity, tends to assume its initial shape after the compression roller has passed and a 90 vacuum is created which draws in the liquid, 95 100

so that when the other compression roller passes, this liquid will be driven to the outlet and expelled while more liquid will be drawn in by the recurrence of a vacuum on the other side.

It will be understood that the pumping of liquid by this apparatus is independent of the weight of the elevation column, and furthermore that the resistances caused by this weight are greatly reduced by the favourable conditions present.

As the closure of the rubber tube caused by the compression rollers is permanent and complete, the liquid suction column is constant so that the pump will always be responsive and capable of immediate use.

I claim:

1. A pump comprising a cylinder, a tube of resilient material extending around the inner circumferential face of the cylinder and having its ends leading out of the cylinder, a shaft axially mounted in the cylinder, a support within the cylinder secured to the shaft and projecting radially therefrom in opposite directions, levers pivoted to the ends of the support, rollers mounted on the free ends of said levers and adapted to bear upon the tube, and rods connecting the free ends of the levers with the opposite ends of the support and adapted to hold the rollers against the tube.

2. A pump comprising a cylinder, a tube of resilient material extending around the inner circumferential face of the cylinder and having its ends leading out of the cylinder, a shaft axially mounted in the cylinder, a support within the cylinder secured to the shaft and projecting radially therefrom in opposite directions, levers pivoted to the ends of the support, rollers mounted on the free ends of said levers and adapted to bear upon the tube, rods connecting the free ends of the levers with the opposite ends of the support and adapted to hold the rollers against the tube, and turnbuckles on the rods for adjusting their lengths to vary the pressure of the rollers on the tube.

JUAN CORNET Y OLIVERAS.
